UNITED STATES PATENT OFFICE.

PHILIP M. REA, OF WEST CHICAGO, ILLINOIS.

WIRE-LINE CLAMP.

1,339,419.

Specification of Letters Patent. Patented May 11, 1920.

Application filed May 8, 1919. Serial No. 295,750.

To all whom it may concern:

Be it known that I, PHILIP M. REA, a citizen of the United States, residing at West Chicago, in the county of DuPage and State of Illinois, have invented a certain new and useful Improvement in Wire-Line Clamps, of which the following is a specification.

My invention relates to cable clamps, especially wire cables in drilling oil and Artesian wells.

The primary object of the invention is to provide a clamp capable of exerting great gripping action upon the cable so as to securely hold the same. Contributory to this general object, it is my purpose to provide a clamp in the form of a linkwork or toggle mechanism. Another object is to provide means for preventing the racking of the linkwork, and instead, equalize the amount of angular movement of the jaws about their pivots. Another object is to provide an advantageous form of combined lug and liner or "slip"—the lug for supporting the clamp and the slip for engaging the cable. Other objects contributing to the general effectiveness of the device will become apparent as the description proceeds.

I accomplish my objects by the mechanism illustrated in the accompanying drawings in which—

Figures 1 and 2 are top plan views of the complete device showing certain of the parts in section. Fig. 1 shows the parts in acting or gripping position and Fig. 2 with the jaws thrown open.

Fig. 3 is a front elevation of the device showing, among other things, the manner of suspending the same.

Fig. 4 is a sectional view on the line 4—4, Fig. 1.

Fig. 5 is a perspective view of three of the principal parts of the device showing them separated and illustrating their co-operating relationship.

Fig. 6 is a diagrammatic view illustrating the function of the equalizing gears which prevent the link work from racking.

Like numerals denote like parts throughout the several views.

The three largest single members of the device are the two jaws 1, 1, and the connecting link 2, shown separately in perspective in Fig. 5. These jaws are pivotally connected to the link at opposite ends thereof by means of the pins 3, 3. In the

design shown said pins are retained in position by means of heads 3^a at one end and cotter pins 3^b at the other, as best shown in Figs. 3 and 4. The inner faces of the jaws have recesses 5 which form seats for the liners or "slips" 6. These are interchangeable and engage the cable or wire line 7. By preference they are drop forgings and terminate at the upper end in lugs or hooks 8 adapted to be suspended from any suitable kind of supporting rigging 9. While the form of the lugs may be varied I have illustrated a particularly advantageous type in which the lugs are integral with the slips 7 and form closed hooks, the outer ends having shoulders 11 which engage the top and fingers 12 which engage the sides of the jaws and therefore serve to brace the parts against the jaw. These characteristics are well illustrated in Figs. 3 and 4. The slips and lugs are secured to the jaws by means of pins 14 mounted in lugs 15 formed at the bottom of the jaws. They are held in place by cotter pins 16 or other suitable fastening elements. The inner faces of the slips 6 have channels 17 which form bearing surfaces for the cable when the jaws are closed.

The recesses 5 are preferably so located that when the jaws are in closed or gripping position as shown in Fig. 1, they will lie near the plane which passes through the axes of the jaw pivots 3, 3. This increases the gripping or toggle action of the jaws upon the cable.

The connecting link 2 is arched or bowed as shown, thus enabling it to pass to one side of the slips for avoiding them and the cable.

In my design the slips are of considerable length, thus gripping a considerable length of the cable. In order to distribute the strain the jaws are branched, and the link 2 fits between the branches. By preference, the link 2 is branched also—that is, is formed in two parts rigidly connected together by a vertical and desirably integral connecting element 2^a shown in perspective in Fig. 5. For the purpose of imparting a finished appearance and rendering the device more convenient to handle, filler blocks 2^b are formed at the top and bottom of the link to come between the adjacent surfaces of the jaws, as best shown in Fig. 1.

In the design illustrated, the jaws have three branches and the middle branches are

provided with gear teeth 20. These intermesh and constitute segmental gears, the axes whereof are coincident with the axes of the pivot pins 3. The function of these 5 gears is illustrated diagrammatically in Fig. 6. It will be evident that in a linkwork consisting merely of two jaws pivoted to the free ends of a link, the mechanism would rack—that is, the parts, being unconfined in 10 their movement, would fail to insure the registering of the slips 6 when the jaws are closed. The jaws could readily move longitudinally relatively to each other as illustrated in Fig. 6. I have prevented this by 15 providing said segmental gears 20, which equalize the amount of rotation of the jaws relatively to the connecting link 2. Differently stated, the segmental gears by meshing with each other compel the two jaws 20 to make equal angular movements with respect to the connecting link. Hence, it is unnecessary for the operator to exercise any particular care in operating the clamp to see to it that the slips register when the 25 jaws are closed. This is accomplished automatically by means of the segmental gears.

In common with other devices of this character the jaws in my clamp are held closed by means of a yoke 24 of any suitable design. In the example illustrated this yoke is supported at one end upon a block 30 mounted between lugs 26, 26 formed at the end of the arm 1^a of one of the jaws. The yoke is pivotally attached to this block 35 and is so formed that its far end may slip over the outer end of the arm 1^b which is integral with the other jaw of the clamp. The block is provided with a clamping screw 27, the inner end of which abuts the 40 side of arm 1^a and makes it possible to draw the arms 1^a, 1^b as closely together as may be desired to obtain the necessary clamping pressure upon the cable. This screw is provided with a handle 28 by which it may be 45 rotated.

The operation will now be readily understood. When the arms 1^a, 1^b are brought toward each other they cause the jaws to rotate about their pivot pins 3 and bring 50 the slips 6 into engagement with the cable. As a result of the fact that when the slips are in contact with the cable they will lie near the plane defined by the axes of the pivot pins 3, 3, a very high degree of pressure 55 of the slips upon the cable may be generated through the exerting of only a normal amount of pressure of the yoke 24 upon the arms 1^a, 1^b. This is due to the toggle like action of the device, the gripping force 60 or pressure of the slips upon the cable being almost at right angles to the direction of motion of the slips at the moment, due to the rotation of the jaws about the pivot pins. Differently stated, when the jaws are 65 closed, any additional rotary movement of

the jaws will produce a much greater movement of the slip angularly than in a direction toward the cable. Thus the gripping action is greatly multiplied.

It will be noted that in order to avoid the 70 cable when the device is in acting position, the link 2 is bowed, which enables it to pass to one side of the cable and slips. It will be noted also that the segmental gears 20 are located at one side of the plane passing 75 through the axes of the pivot pins 3. This permits them also to avoid interference with the cable or slips.

My construction lends itself readily to the use of pivot pins 3 of large diameter. 80 The result is that there is practically no danger of shearing the pins when the device is in active use.

Having thus described my invention what I claim as new and desire to secure by 85 Letters Patent, is:—

1. A cable clamp having a link, jaws pivoted to the ends of the link and adapted to grip the cable between them, the pivotal axes being parallel to the gripped portion 90 of the cable, arms for rotating the jaws about their pivots and holding them in gripping position, and gears rigidly fastened to said jaws and meshing with each other for compelling the jaws always to rotate equal amounts about their pivots. 95

2. A cable clamp having a link, a pair of jaws pivoted to the link at the ends thereof, said jaws having recesses in their inner faces for the reception and engagement of 100 the cable, said recesses being so placed that when the jaws are in closed, gripping position the said recesses will be near the plane defined by the axes of the jaw pivots, arms rigidly fastened to and extending from said 105 jaws whereby they may be rotated about their pivots, and means for equalizing the amount of rotation of the jaws about their pivots.

3. A cable clamp having a link, a pair 110 of jaws pivoted to the link at the ends thereof, said jaws having recesses in their inner faces for the reception and engagement of the cable, said recesses being so placed that when the jaws are in closed, gripping position the said recesses will be near the plane 115 defined by the axes of the jaw pivots, arms for rotating said jaws about their pivots, and gears rigidly fastened to said jaws concentric with their pivots, said gears meshing with each other for equalizing the angular movement of the jaws about their pivots. 120

4. A cable clamp having a link, a pair 125 of jaws pivoted to the ends of the link and having recesses in their inner faces for the reception of the cable, said recesses being approximately in the plane containing the axes of the pivot when the jaws are in gripping position, and means for equalizing the 130

amount of rotation of the jaws about their pivots, said equalizing means being located chiefly at one side of said plane for non-interference with the cable when the jaws 5 are in gripping position.

5. A structure as specified in claim 4 in which the equalizing means are in the form of intermeshing gears rigidly fastened to the jaws.

10 6. A cable clamp comprising a link, a pair of jaws pivoted to the ends of the link, the inner faces of the jaws being adapted to grip the cable between them, a portion of the inner faces of the jaws being curved and 15 concentric with the pivots, the jaws being branched and adapted to receive the link between their branches, filler blocks on said link for filling the spaces between the curved inner spaces of the jaws when the 20 latter are in gripping position, and means for equalizing the amount of rotation of said jaws about their pivots.

7. A clamp for gripping upright cables for well drilling and similar purposes, said 25 clamp having a link, a pair of jaws pivoted to the ends of the link thereby forming a pivot jointed link-work, the pivotal axis being parallel to the gripped portion of the cable, said jaws having recesses in their

inner faces, slips in the form of liners for 30 the jaws, said slips being adapted to seat in said recesses and adapted to engage the cable, arms for rotating the jaws about their pivots and holding them in gripping position, and a pair of segmental spur gears 35 rigidly fastened to the respective jaws and meshing with each other for compelling the jaws always to rotate equal amounts about their pivots to thereby prevent the linkwork from racking and bring the acting surfaces 40 of the slips into register with each other when the jaws are closed.

8. A cable clamp comprising a link, a pair of jaws pivoted to the ends of said link, said jaws having recesses in the inner faces, 45 slips in the form of liners for the jaws, said slips being adapted to seat in said recesses and adapted to engage a cable and hooks formed at the upper ends of the slips to afford means whereby the clamp may be suspended, each hook having a shoulder at the 50 outer end adapted to abut the top of the jaw on which it is mounted and having a finger adapted to engage the side of said jaw for bracing the hook.

In witness whereof, I have hereunto subscribed my name.

PHILIP M. REA.
